UNITED STATES PATENT OFFICE.

WALTER J. WELCH AND ATLEE H. TRACY, OF CHICAGO, ILLINOIS, ASSIGNORS TO H. M. BYLLESBY & COMPANY, OF CHICAGO, ILLINOIS, A CORPORATION OF DELAWARE.

ELECTRICAL INSULATOR.

1,393,330.

Specification of Letters Patent. Patented Oct. 11, 1921.

Application filed April 17, 1919. Serial No. 290,851.

To all whom it may concern:

Be it known that we, WALTER J. WELCH and ATLEE H. TRACY, citizens of the United States, and residents of Chicago, in the county of Cook and State of Illinois, have invented a certain new and useful Improvement in Electrical Insulators, of which the following is a specification.

This invention relates to electrical insulators of the general type which forms the subject-matter of U. S. Letters Patent No. 1,110,934, dated September 15, 1914, and relates particularly to such insulators when connected in series, as commonly applied to high tension lines.

The object of the invention is to provide an improved coupling for connecting the ends of the metallic loops or links used to connect the individual insulator disks comprising a complete insulator, which will be simple in construction, which will provide a joint or connection which will be sufficiently strong to withstand any stresses to which it may be subjected in use, and which may be quickly and conveniently applied in the field without the use of special tools or equipment of any kind.

To this end, our improved coupling comprises a tubular shell at the ends of which interior shoulders are formed adapted to interlock with shoulders formed on the ends of the loop or link which connects adjacent insulator elements. Said shell is divided lengthwise to form complementary segments, preferably two, which are adapted to be secured together in assembled position by a ferrule or the like applied to the outside thereof.

In the accompanying drawings, in which our invention is fully illustrated,

Figure 1 is a sectional elevation of an insulator indicating the application of our invention.

Figs. 2 and 3 are top plan views of adjacent insulators showing the arrangement of the holes therein for making connections thereto.

Fig. 4 is a longitudinal sectional view, on an enlarged scale, of our improved coupling; and

Fig. 5 is a sectional view thereof on the line 5—5 of Fig. 4.

Referring now to the drawings, A designates, as a whole, an insulator comprising a plurality of insulator elements 1 connect-

ed in series by means of metallic links or loops 2 to form an insulator having great electrical resistance and particularly adapted for use on high tension lines.

The insulator elements 1 are of the type 60 of that which forms the subject-matter of U. S. Letters Patent No. 1,110,934, dated September 15, 1914, and will be readily understood by skilled electricians from an examination of the drawing without a description in detail thereof. However, if for any reason, a full description thereof is desired, it may be had from said U. S. Patent No. 1,110,934 to which reference is made.

A distinguishing characteristic of this 70 type of insulator is the provision of means on opposite sides thereof for making connections thereto, together with means for diverting rain from the under side thereof. Specifically, said attaching means consists of 75 curved holes or openings 3 and 4 formed in opposite sides of said insulator elements, the walls of which are continuous so as to prevent leakage therethrough to the opposite side thereof, and the loops of which 80 extend through each other. Said holes or openings are adapted to receive the metal links or loops 2, which are preferably flexible so as to facilitate inserting them through said holes or openings, being either made of 85 heavy copper wire or of flexible metal cable or wire the ends of which are adapted to be connected by means of a suitable coupling.

In the preferable construction shown, each of said links or loops consists of two 90 similar members, preferably made of strong steel wire, which are bent between their ends to provide for inserting them through the holes 3 and 4 formed in the adjacent sides of connected insulator elements 1 and also 95 to conform to the seats on said insulator elements formed by said holes 3 and 4.

The ends of the members formed in said links or loops are connected by means of suitable coupling means, designated as a 100 whole B, to form the finished links or loops and thus to connect the insulator elements 1.

In accordance with our invention, the coupling means for thus connecting the ends of the members of said links or loops 2 consists of heads 5 formed on the ends of said link members and a tubular shell 6 formed at the ends of which are interior shoulders 7 which are adapted to interlock with shoulders 8 formed on the heads 5, said shoulders 105

preferably extending substantially at right angles to the direction of the pull or tension which the insulator A will sustain in use, thereby eliminating practically all components of stress in said coupling other than in the direct line of tension.

To provide for applying the coupling B to the heads 5 on the link members to be connected, said coupling shell is preferably 10 divided lengthwise into complementary segments, preferably two similar segments, which, after being adjusted to the heads 5 with the shoulders 7 and 8 in interlocked position, are secured together by means of a 15 ferrule 9 applied to the outside of said tubular coupling shell.

Said coupling shell is preferably made of 20 steel or other strong metal of such thickness that it will be sufficiently strong to withstand any stresses to which it will be 25 subjected in use, and in any event, as strong as other portions of said links or loops 2.

In assembling the coupling, the ferrule 9 which holds the parts of the coupling shell 30 together, is first placed over the end of one of the members which is to be connected, preferably the end of that member which will be uppermost in use. The parts of the coupling shell are then adjusted to the heads 35 on the ends of the link or loop members to be connected, after which the ferrule 9 is slipped down over said coupling shell, which will hold the members of said coupling shell in engagement with the heads on the ends of the connected links or loops.

Due to the fact that, in use, practically 40 the only stresses which the coupling B will sustain will be at right angles to the engaging shoulders 7 and 8, and that practically no stresses will be developed therein tending 45 to force the parts or members of the coupling shell apart, the only function which the ferrule 9 will perform will be to hold the parts of said coupling shell together and it may, therefore, be made relatively light. In practice, we contemplate making 50 the side walls of said coupling shell about 10 gage in thickness and the thickness of the ferrule 9 about 22 gage. Obviously, however, the thickness of said shell and ferrule, respectively, may be varied as desired to meet varying requirements.

The ferrule 9 is maintained in adjusted 55 position on the coupling shell by means of flanges 10 on opposite ends thereof which embrace opposite ends of said coupling shell. In practice, the flange 10 at one end of said ferrule will preferably be formed before 60 said ferrule is adjusted to the coupling shell, while the flange at the other end is designed to be formed after said ferrule has been adjusted in position, which may be

done quickly and conveniently by making said ferrule somewhat longer than the coupling shell and bending the projecting end 65 thereof inwardly over the end of said coupling shell, which can readily be done by means of pliers or a hammer, which are always available in the field. Also, to provide for easily bending over the projecting 70 end of said ferrule, parts thereof may be cut away, so as to form spaced lugs or lips, indicated in dotted lines at 10' in Fig. 4, which may be easily bent over the end of the coupling shell. 75

With the described construction, it is obvious that our improved coupling may be finished complete at the shop and that all 80 that will be required to apply the same either in the original installation or in making repairs, will be to assemble the various parts and bend or crimp the projecting ends of the ferrule 9 over the end of the coupling shell.

Owing to the greater flexibility of 85 metallic cable and the greater ease with which it may be inserted through the holes in the insulator elements 1, a single continuous length of said flexible metal cable may be employed, in which event only a single 90 coupling will be required to connect the ends thereof. As regards its mechanical features, however, the construction of said coupling will be the same as where two-part links or loops are employed, thus rendering necessary 95 two couplings.

We claim:—

A coupling comprising a cylindrical shell 100 of even diameter throughout its length and consisting of two similar longitudinal segments, said shell being provided with a bore 105 adapted to receive the ends of the parts to be connected, said bore being provided with shoulders extending entirely around the shell and constructed and arranged to interlock with corresponding shoulders on said 110 parts to be connected, a cylindrical ferrule fitted to the exterior of said coupling shell and having a flange at one end thereof of a width to extend over an end of said coupling shell and leave an opening sufficiently large 115 to pass over the shouldered end of either of the members to be connected, and lugs on the opposite end of the ferrule adapted to be bent over the other end of the coupling shell to secure the ferrule in engagement with the shell and said shell in engagement with the coupled parts.

In testimony that we claim the foregoing as our invention, we affix our signatures 120 this 10th day of April, 1919.

WALTER J. WELCH.
